UNITED STATES PATENT OFFICE

2,048,119

STRAIGHT LINE PUMPING JACK

Fred Graham, Lufkin, Tex., assignor to Lufkin
Foundry & Machine Company, a corporation

Application March 28, 1935, Serial No. 13,453

7 Claims. (Cl. 74—103)

The invention relates to an improvement in straight line pumping jacks and particularly of the type used in lifting oil and water from wells wherein a pump is located at the bottom of the well and is operated by means of a string of sucker rods which are reciprocated by a suitable power mechanism and the oscillation of a walking beam.

In devices of this type it is desirable to have the reciprocatory motion of the polish rod which extends from the well head occur in a perfectly straight line vertical movement. With the oscillation of a walking beam member for transmitting the power to the polish rod, however, such an arrangement is impossible unless a specific mechanism is provided for the purpose of avoiding the oscillation of the top end of the polish rod due to the fact that the end of the walking beam oscillates in an arc as it rocks about the center bearing.

It is one of the objects of the present invention to provide a mechanism attachment for the Samson post, walking beam, and polish rod whereby the oscillation of the end of the walking beam is transformed into a vertical straight line motion.

Another object of the invention is to provide an attachment mechanism for the walking beam so that the upper end of the polish rod is restrained to travel in a vertical path.

Still another object of the invention is to provide an oscillating connection between the polish rod and the end of the walking beam so that the oscillation of the end of the walking beam is taken up by the pivoted connection and not imparted to the polish rod.

A still further object of the invention is to provide a linkage mechanism whereby the various pivot arms are so proportioned that the upper end of the polish rod is constrained to travel in a vertical path.

Another object of the invention is to provide a linkage mechanism wherein the oscillation of the end of the walking beam is counteracted by a proportional oscillation of a linkage mechanism to prevent the transfer of the oscillating movement to the polish rod.

A still further object of the invention is to provide a four-bar linkage arrangement for so anchoring the top of the polish rod that it is restrained to reciprocate in a vertical position.

Other and further objects of the invention will be readily apparent when the following description is considered in connection with the accompanying drawing, wherein:

Fig. 1 is a side elevation of a diagrammatic view showing a general arrangement and construction of the pumping equipment and illustrat-

ing a Samson post, walking beam and well head connection to which the invention has been applied.

Fig. 2 is a section taken on the line 2—2 of Fig. 1 and looking in the direction of the arrows.

The usual construction in pumping equipment of this type to provide a power mechanism is illustrated generally at 2. By means of this power mechanism rotation is imparted to the shaft 3 of the pumping unit 4. This shaft carries a suitable crank arm 5 which may have the weight 6 attached thereto, and to which the pitman rod 8 is also connected. As the shaft 3 rotates an oscillating movement is imparted to the upper end 9 of the pitman rod 8 and it is at this point that the walking beam 12 is connected by means of the pivot shaft 13.

The walking beam 12 is mounted upon a center iron 15 which is mounted on the Samson post 16 in a manner well known in the oil fields. A walking beam rest 17 may be provided on the Samson post to support the walking beam when it is disconnected from the well head, which is indicated at 20.

The pump for raising the liquid from the well is located at the bottom of the well and has connected thereto a string of sucker rods 21. These rods terminate in a polish rod section 22 which is arranged to pass through a stuffing box 23 in the top of the well head. A polish rod hanger 25 is connected by the coupling 26 to the upper end of the polish rod. In the usual forms of the invention this hanger 25 is mounted directly on the end of the walking beam and is caused to move up and down upon oscillation of the walking beam 12.

Needless to say that the end 26 of the walking beam 12 negotiates an arc of a circle because of the fact that it is pivoted at 15 and is caused to rock back and forth upon the center iron bearing 15. The amount of lateral movement negotiated by the end of the walking beam during its oscillation would, of course, tend to move the polish rod section 22 to the right and to the left as viewed in Fig. 1. This causes a wear on the rod in the stuffing box 23 and it is one of the objects of this invention to avoid any such oscillation and to maintain the polish rod section 22 and the hanger 25 in the same vertical plane at all times so that the polish rod will move smoothly through the stuffing box 23.

A pair of links 30 have been provided as a connection between the pivot pin 31 mounted on top of the end 26 of the walking beam 12 and the pivot pin 32 which extends beneath the lower

end of the walking beam 12. These two links are best seen in end view in Fig. 2, and tend to straddle the walking beam 12 to form a link which is free to pivot about the pin 31 as a center.

5 The hanger 25 is seen in Fig. 2 as having two spaced legs 33 which are mounted on the pin 32. Between the links 30, however, an arm 35 has the pin 32 passed through the right hand end, and, as viewed in Fig. 1, is positioned between the two 10 legs 33 of the hanger 25. This arm 35 extends along the lower side of the walking beam 12 in a substantially horizontal position when viewed with the parts shown as in Fig. 1.

15 The left hand end of this arm 35 carries a shaft or pivot pin 36 which receives the upper end of a connecting bar 37 which straddles the arm 9 and has the pin 36 passed therethrough.

Intermediate the ends of the bar 37 is a bearing shaft 38 whose position is fixed because of 20 the brackets 39 which are fixed to the walking beam 12 between the end 26 and the center iron 15.

25 The lower end of the bar 37 carries the pin or shaft 41 and has the anchor leg 42 pivoted thereto. The left hand end of this anchor leg 42 is pivoted at 43 to a clamp 44 which is fixed on the Samson post 16.

30 The leg 42, the bar 37, the arm 35 and the links 30 are pivoted together to form a four-bar linkage having the three intermediate pin pivots 41, 36, and 32, and the two anchor shafts 43 and 31.

35 The brackets 39 are so positioned on the walking beam at the proper distance between the center iron 15 and end of the beam 26 where the shaft 31 is mounted, that the shaft 38 carried by the lower end of the brackets will have movement which is directly in proportion to the movement of the pin 31. The amount of variation from a 40 vertical plane due to the oscillation of the walking beam, however, will be less with the shaft 38 than with the pin 31. The bar 37 is so mounted on the shaft 38, however, that the upper portion thereof is of greater length than the lower portion. 45 These proportions will be so arranged that when the anchor leg 42 is held stationary because of its pivoting on the pin 43 it will cause oscillation of the arm 38 upon oscillation of the walking beam.

50 The length of the leg 42, bar 37, arm 35 and the link 30 are so proportioned that when the location of the brackets 39 and the shaft 38 are considered that the path of the shaft 32 will be on a vertical line. The parts are shown in their 55 respective positions in Fig. 1 so that they will control the operation of the polish rod 22, to compel a straight line movement thereof.

56 It is understood that the position of the pivot pins or shafts may be adjusted in accordance with stroke desired in order to obtain a straight lift or straight line movement of the upper end of the polish rod.

What is claimed is:

1. A straight lift pumping device including in combination a Samson post, a walking beam pivoted thereon, a power mechanism connected to one end of said beam, a member connecting a lift device to the other end so that rocking movement of the beam actuates the lift device, and a straight line guide means for the lift device comprising a bar pivoted on said walking beam, a leg connected to said post and to one end of said bar, and an arm connected to said member and the other end of said bar. 5

2. A straight lift device for connecting the oscillating end of a walking beam and the pump rod comprising a link pivoted to the beam and rod, an arm connected to the lower end of said link, a rocker bar connected to the other end of said arm and pivotally mounted on the beam, and an anchor leg pivoted to the other end of said bar. 10

3. A straight lift device for connecting the oscillating end of a walking beam and the pump rod comprising a link pivoted to the beam and rod, an arm connected to the lower end of said link, a rocker bar connected to the other end of said arm and pivotally mounted on the beam, 25 and an anchor leg pivoted to the other end of said bar, whereby said link is moved by said arm in proportion to the rocking of said bar by oscillation of the beam. 20

4. A straight lift device for pumping rigs including a Samson post, a walking beam pivoted thereon, a pump rod member pivoted adjacent the end of said beam, a bracket fixed to said beam between said end and said post, a bar pivoted on said bracket, a leg connecting one end 30 of said bar to said Samson post, an arm connecting the other end of said bar to said member whereby said member is pivoted as said beam rocks so that a straight line pull is exerted by said member. 40

5. In a pumping installation, a Samson post, a walking beam thereon, a pump rod, links at one end of said beam, means connecting said links and said rod, a rocking bar on said beam between said post and said links, means connecting one 45 end of said bar and said post and means connecting the other end of said bar and said links. 45

6. In a pumping installation, a Samson post, a walking beam thereon, a pump rod, links at one end of said beam, means connecting said 50 links and said rod, a rocking bar on said beam between said post and said links, an arm connected between the upper end of said bar to said links, and a swinging member connecting the other end of said bar to said Samson post. 55

7. A Samson post, a walking beam thereon, links pivotally mounted at one end of said beam, a pump rod connected with said links, an arm pivotally connected with said links, an anchor leg connected with said post, and a rocking bar between said links and said post connecting said leg and said arm. 60
